CONTAINERIZATION OF TETRAHEDRON-SHAPED PACKAGES

James W. Morris, Framingham, and Harold T. Crossley, 5
Foxboro, Mass., assignors to Packaging Frontiers, Inc.,
Waltham, Mass., a corporation of Delaware

Filed May 4, 1966, Ser. No. 547,649
10 Claims. (Cl. 53—142)

This invention relates to the containerization of tetrahedron-shaped packages, and more particularly to apparatus for automatically packing such packages in rectangular containers.

The invention is particularly concerned with a containerization of tetrahedron-shaped packages produced in quantity production by machines such as shown, for example, in the copending coassigned Wagner et al. U.S. patent application Ser. No. 261,795, filed Feb. 28, 1963, and the coassigned Murray U.S. Patent 3,221,469, issued Dec. 7, 1965. It is desirable that apparatus be provided for automatically packing the packages in cartons or boxes. One type of pack which has been found particularly suitable for tetrahedron-shaped packages is a type that may be referred to as the fan-pack, in which a rectangular container, such as a cardboard carton or tray of square outline in plan, is packed with packages arranged in sets each shaped like a fan, each set consisting of a plurality of packages with one end of each package in the set at the apex of the fan and the other ends of the packages in the set constituting the outer edge of the fan, a first set being positioned in the container with its apex at a first corner of the container, a second set being positioned in the container overlying the first set with its apex at a second corner of the container, a third set being positioned in the container overlying the second set with its apex at a third corner of the container, and a fourth set being positioned in the container overlying the third set and with its apex at the fourth corner of the container. Such a pack is disclosed in the copending coassigned Boynton U.S. patent application Ser. No. 185,326, filed Apr. 5, 1962, now Patent No. 3,250,386. A prior apparatus for fan-packing tetrahedron-shaped packages in such manner is shown in the copending coassigned Anderson U.S. patent application Ser. No. 268,265, filed Mar. 27, 1963, now Patent No. 3,282,024. Among the several objects of the present invention may be noted the provision of improved apparatus for automatically effecting the fan-packing of tetrahedron-shaped packages in rectangular containers at a rapid rate, involving the feeding of packages forward in a predetermined generally horizontal path with the packages lined up in rows extending longitudinally with respect to the direction of feed and with the end seals at the leading ends of the packages upright, arresting packages, one from each row, and forming the packages into a fan, and transferring each fan to a container after formation of the fan. Other objects and features will be in part apparent and in part pointed out hereinafter.

The invention accordingly comprises the constructions hereinafter described, the scope of the invention being indicated in the following claims.

In the accompanying drawings, in which several of various possible embodiments of the invention are illustrated,

FIG. 1 is a plan of a first version of the fan-packing apparatus of this invention;

FIG. 2 is a side elevation of FIG. 1;

FIG. 3 is a perspective of a detail of the apparatus shown in FIGS. 1 and 2;

FIG. 4 is a plan of a second version of the fan-packing apparatus of this invention;

FIG. 5 is a side elevation of FIG. 4;

2

FIG. 6 is a plan of a third version of the fan-packing apparatus of this invention;

FIG. 7 is an enlarged view in elevation on line 7—7 of FIG. 6;

FIG. 8 is a horizontal section on line 8—8 of FIG. 7; and

FIG. 9 is a plan of a fourth version of the fan-packing apparatus of this invention.

Corresponding reference characters indicate several views of the drawings.

Referring to the drawings, first to FIGS. 1 and 2, there is indicated at 1 an endless belt conveyor trained around horizontal rolls, one of which is indicated at 3, to have an upper horizontal reach 5, which constitutes its working reach, and a lower horizontal reach 7, which constitutes its return reach. The belt is continuously driven by any suitable drive such as indicated at 9 for travel of its working reach from left to right as shown in FIGS. 1 and 2. The working reach 5 of the belt conveyor is adapted to feed tetrahedron-shaped packages P forward with the packages lined up in a plurality of side-by-side rows extending longitudinally of the conveyor, and with the packages in each row spaced from one another lengthwise of the conveyor. As shown in FIG. 1, there are three such rows, designated R1, R2 and R3, for forming fans consisting of three packages each. The packages may be aligned transversely of the conveyor in groups of three, but it will be understood that such transverse alignment is not essential.

Each package P, as is conventional, comprises a tube having seals E1 and E2 at its ends with these end seals at right angles to one another (accounting for the tetrahedron-shape of the package). The packages lie on the upper reach of the conveyor with the end seals E1 at the leading ends of the packages extending upward from the conveyor. Packages P are delivered from the machine (not shown) by means of which they are produced to the conveyor 1 by a delivery conveyor and a diverter (not shown). The delivery conveyor is, for example, an endless belt conveyor of relatively narrow width, and delivers packages in single file one after another to the diverter, with the end seals E1 of the packages at the leading ends of the packages and standing up in a vertical plane. The diverter, which is a conventional commercially available unit such as an Illumitronic Channelizer, Model CH 3-12-20, sold by Illumitronic Systems Corporation of Sunnyvale, Calif., is adapted to allow certain packages to proceed straight ahead to form the center row R2 of packages on conveyor 1, to divert other packages to one side to form row R2, and to divert still other packages to the other side to form row R3.

The packages P on the working reach 5 of belt conveyor 1 are conveyed thereby in rows R1, R2 and R3 toward the leading end of reach 5 (its right-hand end as viewed in FIGS. 1 and 2 where the belt conveyor is trained around roll 3). Just before a group of three packages (one from each row) reaches the leading end of the working reach 5 of the belt conveyor 1 the group of three is caught in a V-shaped collector 11 overlying reach 5 adjacent its said leading end and formed into a fan therein. As shown herein, the tetrahedron-shaped packages P are what are called 30° tetrahedrons, so that three of them fan together in a fan having a subtended angle of 90° at its apex. Collector 11 accordingly has two arms 13 branching at 90° from its apex 15. It is mounted in fixed horizontal position above the working reach 5 of the conveyor 1 with its apex 15 in the plane of the central row R2 of packages and toward the leading end of the conveyor and with its arms 13 branching out at 45° angles to the plane of the central row R2 by means of a bracket 17 which extends rearward from a post 19 ex-

tending upward from base 21 of the apparatus outward of and adjacent the leading end of the conveyor.

As will be seen, the packages in the central row R2 move forward with the working reach 5 of conveyor 1 in line with the apex 15 of the collector. Arms 13 of the collector are of such length as to extend beyond and intersect the planes of the two outer rows R1 and R3 of packages. Consequently, as any given package of central row R2 reaches the collector, the leading end seal E1 of this package engages the apex of the collector and is arrested in a central position in the collector. The leading end seals E1 of the two corresponding packages in the outer rows R1 and R3 engage the arms 13 at points 13a and, since these two packages continue to be urged forward by the conveyor 1 (which travels continuously), they are caused to wedge into the collector on opposite sides of the central package, so that the three packages are collected in the collector as a fan F. End seals E1 of the three packages constitute the apex of the fan, and end seals E2 of the three packages constitute the outer edge of the fan.

At 23 is indicated means for holding a container C in fan-receiving position outward of and adjacent the leading end of the working reach 5 of the conveyor 1. As illustrated, this comprises a platform 25 on the upper end of a vertical shaft 27 extending up from an indexing drive mechanism indicated at 29 adapted rotatably to index the shaft and platform in 90° intervals. The shaft is located in the plane of central row R2 (the central plane of conveyor 1). The container C is shown as a square open-topped carton. The four corners of the carton are designated C1, C2, C3 and C4. The indexing drive is adapted intermittently to index the platform around in 90° index intervals to four indexed positions, in the first of which corners C1 and C3 are located in the central plane of the conveyor with C3 toward and C1 away from the conveyor, in the second of which corners C2 and C4 are located in the central plane of the conveyor with C4 toward and C2 away from the conveyor, in the third of which corners C3 and C1 are located in the central plane of the conveyor with C1 toward and C3 away from the conveyor, and in the fourth of which corners C4 and C2 are in the central plane of the conveyor with C2 toward and C4 away from the conveyor.

At 31 is indicated means for effecting transfer to the container of fans collected in the collector 11. This transfer means is shown to comprise what amounts in effect to a parallelogram linkage 33 including an upper arm 35 pivoted at 37 on the post 19 and a lower arm 39 pivoted at 41 on the post for swinging movement on horizontal axes which extend transversely with respect to the conveyor. Pivot 41 is directly below pivot 37. The outer free ends of the arms are connected by a bar 43 parallel to the post, pivotal connections between the arms and this bar being indicated at 45 and 47. A bracket 49 extends horizontally from bar 43 and transversely with respect to the conveyor and has three holes therein with a vertically extending sleeve 51 fixed in each hole (see also FIG. 4). Vertically slidable in each sleeve is a tubular rod 53. At the lower end of each rod is a rubber vacuum gripper cup 55. Flexible vacuum lines 57 are connected to the upper ends of the rods. The rods are adapted to slide downward freely in the sleeves. Collars 59 on the rods are engageable with the upper ends of the sleeves 51 for limiting the downward sliding of the rods.

The location of pivots 37 and 41 and the length of arms 35 and 39 from pivots 37 and 41 to pivots 45 and 47 are such that the parallelogram linkage is swingable between the fan pick-up position illustrated in solid lines in FIG. 2, wherein the vacuum gripper cups 55 at the lower ends of rods 53 are engaged with the three packages P caught and formed into a fan F in collector 11, and the fan placement position illustrated in dotted lines in FIG. 2, wherein the fan F picked up by the rods is placed in the container C with the apex of the fan at that corner of the

container which is in the central plane of the conveyor and away from the conveyor. At 61 is indicated means for swinging the parallelogram linkage between its stated positions, shown as comprising an air cylinder 63 having its piston rod 65 connected to a crank 67 on a gear 69 in mesh with a gear 71 on pivot 41.

In the operation of the apparatus shown in FIGS. 1-3, packages P are continuously conveyed forward in rows R1, R2 and R3 on the upper working reach 5 of belt conveyor 1 toward the collector 11. At the start of any given cycle of operation, container C on platform 25 is empty. Linkage 33 occupies a position such that the lower ends of rods 53 with the vacuum gripper cups 55 thereon are clear of packages moving into the collector. As soon as the first group of three packages P is caught in the collector 11, and arranged into fan F therein, linkage 33 is swung over a fan pick-up position shown in solid lines in FIG. 2, bringing vacuum gripper cups 55 down into engagement with the upper faces of the three packages in the fan caught in the collector. Vacuum applied to the gripper cups via vacuum lines 57 and the tubular rods 53 causes the packages to be gripped to the lower ends of the rods. The linkage is then swung over to its fan placement position, shown in dotted lines in FIG. 2, the fan F of three packages gripped to the cups at the lower ends of the rods thereby being carried over to the container C and placed therein with the apex of the fan at the first corner C1 of the container. The vacuum in the cups 55 is cut off and the cups are vented for release of the packages so that the cups may return empty to pick up a second fan.

While placement of the first fan is occurring as above described, a second group of three packages P is being conveyed forward on the upper working reach of the conveyor 1 and is caught in the collector 11 to form a second fan. As soon as this occurs, linkage 33 (having transferred the first fan to the container) is swung back to pick up the second fan. As it swings back, the platform 25 is indexed around 90° to bring corner C2 into the loading position. After the linkage 33 has been swung back to fan pick-up position and cups 55 have gripped the three packages in the second fan, the linkage swings over to fan placement position to place the second fan in the container with the apex of the second fan in corner C2 of the container, and with the second fan overlying the first fan. The vacuum in the cups 55 is cut off and the cups are vented for release of the packages so that the cups may return empty to pick up a third fan.

While placement of the second fan is occurring as above described, a third group of three packages P is being conveyed forward on the upper working reach of the conveyor 1 and is caught in the collector 11 to form a third fan. As soon as this occurs, linkage 33 (having transferred the second fan to the container) is swung back to pick up the third fan. As it swings back, the platform 25 is indexed 90° to bring corner C3 into the loading position. After the linkage has been swung back to fan pick-up position and cups 55 have gripped the three packages in the third fan, the linkage swings over to fan placement position to place the third fan in the container with the apex of the third fan in corner C3 of the container, and with the third fan overlying the second fan. The vacuum in the cups 55 is cut off and the cups are vented for release of the packages so that the cups may return empty to pick up a fourth fan.

While placement of the third fan is occurring as above described, a fourth group of three packages P is being conveyed forward on the upper working reach of the conveyor 1 and is caught in the collector 11 to form a fourth fan. As soon as this occurs, linkage 33 (having transferred the third fan to the container) is swung back to pick up the fourth fan. As it swings back, the platform is indexed 90° to bring corner C4 into the loading position. After the linkage has been swung back to fan pick-up position and cups 55 have gripped the three packages in the fourth fan, the linkage swings over to fan placement posi-

tion to place the fourth fan in the container with the apex of the fourth fan in corner C4 of the container, and with the fourth fan overlying the third fan. The vacuum in the cups 55 is cut off and the cups are vented for release of the packages so that the cups may return empty to pick up the first fan of the next series. The packed container C is removed and a fresh container C placed on the platform 25.

FIGS. 4 and 5 illustrate a modification of the above in which, instead of picking up the fan by means of the vacuum gripper cups 55, the collector 11 is raised to allow the fan F (after its formation in the collector) to be conveyed by the belt conveyor 1 and fed into the container C off the end of the working reach 5 of the belt conveyor. As shown therein, the platform 25 is located below the level of the working reach 5 to hold the container in position for sliding entry of fans, and a slide 81 is provided at the leading end of reach 5 down which fans may slide into the container. The collector 11 is shown as mounted on an arm 83 pivoted at 85 on a post 87 which extends up from base 21 at one side of the platform 25, leaving the way clear for fans to slide down the slide into the container C. Means such as the air cylinder indicated at 89 is provided for swinging the collector 11 between the lowered package-catching position in which it is shown in solid lines in FIG. 5 and the raised release position shown in dotted lines in FIG. 5 above the fan F caught in the collector to permit the fan to move forward. A fan sliding down the slide into the container is shown in phantom in FIGS. 4 and 5.

FIGS. 6-8 illustrate a further modification of the above in which a wider endless belt conveyor, designated 1a, is used to feed packages P forward in four columns A1, A2, A3 and A4, each consisting of three rows of packages R1, R2 and R3. Extending transversely with respect to the conveyor 1a at its leading end is an endless horizontal chain conveyor 91 carrying a series of platforms 25a (which correspond to platform 25) at equal intervals around its periphery corresponding to the spacing of columns A1-A4. Conveyor 91 has an intermittent index drive indicated at 93 in FIG. 6 for indexing it successively to carry each platform into position at six successive stations designated SA, SB, S1, S2, S3 and S4. Stations SA and SB are container loading stations where containers are applied to the platforms. Stations S1, S2, S3 and S4 are package loading stations in line, respectively, with columns A1, A2, A3 and A4. The platforms 25a are mounted on shafts 95 rotatably mounted on the conveyor 91.

Each platform, at stations SA and SB, occupies a loading position squared off with respect to the conveyor with two sides extending in the direction of the length of the conveyor and its other two sides transverse to the conveyor. Means is provided for indexing each platform through a 45° interval of rotation as it travels from station SB to station S1 to bring it into a diagonal position relative to the conveyor, for indexing it through a 90° interval of rotation as it passes from station S1 to S2, through another 90° interval of rotation as it passes from station S2 to S3, through another 90° interval of rotation as it passes from station S3 and S4, and then through a 45° interval of rotation to bring it back to its initial position for stations SA and SB. As shown in FIGS. 7 and 8, this means for rotatably indexing the platforms comprises a Geneva wheel 97 on each shaft, a series of pins 99, 101, 103 and 105 which are fixed with respect to each conveyor and located at stations S1, S2, S3, S4, and three fixed cam rails 107, 109 and 111 located between stations S1, S2, S3 and S4. Each Geneva wheel is generally square with slots 113 extending diagonally inward from its four corners, and is fixed on its respective shaft in register with the platform on the shaft.

As the conveyor 91 is indexed to carry the platforms from station to station, the slot 113 at the upper right-hand corner (as viewed in FIG. 8) of the Geneva wheel

which was at station SB interengages with the first pin 99, and this causes this wheel and the respective platform to rotate 45° to the position shown for the Geneva wheel at station S1. The upper corner of the Geneva wheel which was at station S1 engages the trailing end of cam rail 107 and this rotates this Geneva wheel and the respective platform 45°. The slot in the wheel which then lies at the upper right-hand corner of the wheel interengages with the second pin 101 and this causes the wheel and the respective platform to rotate another 45°, bringing the wheel into the position shown at station S2. The upper corner of the Geneva wheel which was at station S2 engages the trailing end of cam rail 109 and this rotates this wheel and the respective platform 45°. The slot in the wheel which then lies at the upper right-hand corner of the wheel interengages with the third pin 103 and this causes the wheel and the respective platform to rotate another 45°, bringing the wheel into the position shown at station S3. The upper corner of the Geneva wheel which was at station S3 engages the trailing end of cam rail 111 and this rotates this wheel and the respective platform 45°. The slot in the wheel which then lies at the upper right-hand corner of the wheel interengages with the fourth pin 105 and this causes the wheel and the respective platform to rotate another 45°, bringing the wheel into the position shown at station S4. The wheel which was at station S4 is rotated 45° by reason of the interengagement of the pin 105 in the slot at the upper corner of this wheel, thus bringing it to its squared-off loading position. Guides indicated at 115 are provided for guiding the Geneva wheels in their squared-off loading position from station SA to station SB and for some distance past station SB.

The apparatus shown in FIGS. 6-8 includes four collectors 11a, 11b, 11c and 11d for arresting packages of the four columns A1-A4 and forming the packages into fans. Each of these four collectors corresponds to collector 11 previously described. Collector 11a is lined up with station S1, collector 11b is lined up with station S2, collector 11c is lined up with station S3, and collector 11d is lined up with station S4. Transfer of the fans arrested in the collectors to the containers on the platforms at stations S1-S4 may be effected by means of the type shown in FIGS. 1-3 or by means of the type shown in FIGS. 4 and 5. Whichever type of transfer means is used, the operation involves the formation of a first group of four fans of packages, one in each of the four collectors 11a-11d. With the conveyor 91 dwelling at rest, the fans formed in the four collectors 11a-11d are transferred to the four containers C on the four platforms 25a at stations S1-S4. The transfer of all four fans occurs substantially simultaneously. After the transfer, the conveyor is indexed to carry the container which was at station S1 to station S2, to carry the container which was at station S2 to station S3, to carry the container which was at station S3 to station S4, and to bring an empty container to station S1. The container brought to station S1 is oriented by the Geneva wheel indexing means into the diagonal position for receiving a first fan. The container moving from station S1 to S2 is indexed 90°, the container moving from station S2 to S3 is indexed another 90°, and the container moving from station S3 to S4 is indexed another 90°.

Considering the operation as it applies to one container, the first step is the placement of this container on a platform 25a at station SA or SB. Then, on the next indexing step of the conveyor 91 or the next two indexing steps of the conveyor, the container reaches station S1 and is diagonally oriented as appears in FIG. 6. A fan formed in collector 11a is deposited in the container, the apex of the fan being located in that corner of the diagonally disposed container away from the conveyor 1a. Then, conveyor 91 is indexed to carry the container, with the first fan therein, to station S2, and to rotate the container 90°. This brings a second corner of the container into position

to receive the apex of a fan. Then, a second fan formed in collector S2 is deposited in the container with its apex at the second corner of the container. Then, conveyor 91 is indexed to carry the container, with the first and second fans therein, to station S3, and to rotate the container another 90°. This brings a third corner of the container into position to receive the apex of a fan. Then, a third fan formed in collector S3 is deposited in the container with its apex at the third corner of the container. Then, conveyor 91 is indexed to carry the container, with the first, second and third fans therein, to station S4, and to rotate the container another 90°. This brings the fourth and final corner of the container into position to receive the apex of a fan. Then, a fourth fan formed in collector 11d is deposited in the container with its apex at the fourth corner of the container. This completes the packing of the container, and the packed container is taken off.

FIG. 9 illustrates a further modification of the above in which packages P are fed forward in a single column of three rows by a conveyor 1 as in FIGS. 1 and 4, and collected in a collector 11 to form a single fan, as in FIGS. 1 and 4, and transferred to containers C on platforms 25b carried by and rotating around with a rotary turret 121 which corresponds essentially to the turret indicated at 41 in the aforesaid copending application Ser. No. 268,265. At 123 is indicated a rotary plate of the turret (corresponding to the plate 55 shown in Ser. No. 268,265) and at 125 are indicated frames which extend radially outward from plate 55 and which carry rails 127 (corresponding to frames 57 and rails 65 shown in Ser. No. 268,265). The platforms 25b (which correspond to platforms on tables 69 shown in Ser. No. 268,265) are carried by carriages such as shown at 67 in Ser. No. 268,265 for rotation about their central vertical axes, and are indexable through 90° intervals about their axes in the same manner as shown in Ser. No. 268,265, the arrangement being such that each platform, rotating around with the turret, passes through a loading station indicated at 129 in FIG. 9 adjacent the leading end of the conveyor 1 and aligned with the collector 11 and, after passing through station 129, is indexed 90° on its own axis.

Thus, considering the operation of the FIG. 9 apparatus as regards the packing of a container C on given platforms 25b, when this container (carried by the platform 25b and rotating around with the turret) passes through station 129, a first fan F is transferred from collector into the container with the apex of the fan at a first corner of the container. This transfer may be affected by means of the type shown in FIGS. 1-3 or by means of the type shown in FIGS. 4 and 5. Then, as the container makes a second circuit around with the turret, it is indexed 90° to bring the second corner of the container into position for loading of a second fan into the container with the apex of the second fan at the second corner of the container. Then, as the container makes a third circuit around with the turret, it is indexed 90° to bring its third corner into position for loading of a third fan into the container with the apex of the third fan at the third corner. Finally, as the container makes a fourth circuit around with the turret, it is indexed 90° to bring its fourth corner into position for loading of a fourth fan into the container at the fourth corner of the container, and the container, now packed with four fans, is taken off the platform and a fresh container put on the platform.

In view of the above, it will be seen that the several objects of the invention are achieved and other advantageous results attained.

As various changes could be made in the above constructions without departing from the scope of the invention, it is intended that all matter contained in the above description or shown in the accompanying drawings shall be interpreted as illustrative and not in a limiting sense.

What is claimed is:

1. Apparatus for packing tetrahedron-shaped packages in multicornered containers with the packages arranged in each container in sets each shaped like a fan, each package comprising a tube having seals at its ends with these end seals at right angles to one another, each set consisting of a plurality of packages with one end seal of each package in the set at the apex of the fan and the other end seals of the packages in the fan constituting the outer edge of the fan, and with said fans positioned in the container overlying one another with their apexes at different corners of the container, said apparatus comprising means for feeding packages forward in a predetermined generally horizontal path with the packages lined up in rows extending longitudinally with respect to the direction of feed and with the end seals at the leading ends of the packages upright, means engageable by the packages as they are fed forward by said feeding means for arresting packages, one from each row, and forming the packages into a fan, and means for effecting transfer to a container of each fan after formation thereof by said arresting means.
2. Apparatus as set forth in claim 1 wherein said feeding means comprises an endless belt conveyor having an upper generally horizontal reach on which said packages rest to be fed forward.
3. Apparatus as set forth in claim 2 wherein said arresting means comprises a V-shaped collector overlying said upper reach of the conveyor and arranged with its apex toward the leading end of said upper reach.
4. Apparatus as set forth in claim 1 wherein said transfer means comprises means for gripping and picking up a fan from the arresting means and depositing the fan in said container.
5. Apparatus as set forth in claim 1 wherein said arresting means is mounted for movement between a working position wherein it is engageable by the packages being fed forward and a retracted position clear of a formed fan, and said transfer means comprises means for moving the arresting means to retracted position for forward movement of the fan by said feeding means for delivery of the fan to said container.
6. Apparatus as set forth in claim 1 having means for indexing the container to bring different corners of the container into position for reception of fans of packages.
7. Apparatus as set forth in claim 6 having means for successively presenting a series of containers for reception of fans of packages.
8. Apparatus as set forth in claim 1 having a single arresting means and a single transfer means.
9. Apparatus as set forth in claim 8 having a single container carrier for mounting a single container for being packed with fans, and means for indexing said container carrier to bring different corners of the container into position for reception of fans of packages.
10. Apparatus as set forth in claim 8 having a series of container carriers for mounting a plurality of containers for being packed with fans, means for moving said series successively to present containers at a loading station, and means for indexing said container carriers to bring different corners of the container into position for reception of fans of packages at said loading station.
